MILK BOTTLE OR SIMILAR ARTICLE

Richard T. Cornelius, Minneapolis, Minn., assignor to
The Cornelius Company, Anoka, Minn., a corporation of Minnesota

Filed May 11, 1964, Ser. No. 79,910

Term of patent 14 years

(Cl. D58—8)

FIG. 1 is a side view of a milk bottle, showing my new design.

FIG. 2 is a top view of my design.

The dominant features of my design reside in the stippled portion which is so shaded to indicate a contrasting opaque color.

I claim:

The ornamental design for a milk bottle or similar article, substantially as shown and described.
